(57) **CLAIM**

The ornamental design for a door inside handle for a motor vehicle, as shown and described.

DESCRIPTION

FIG. 1 is a front perspective view of a door inside handle for a motor vehicle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof,

Our design includes a mirror image of the embodiment depicted. The lightly shaded rear surface shown in the figures represents unclaimed, subject matter and forms no part of the claimed design.
